Primary Examiner — Rebekah A Caruso(74) *Attorney, Agent, or Firm* — Revolution IP, PLLC(57) **CLAIM**

The ornamental design for a holder for mobile phones as shown and described.

DESCRIPTION

1.1 : Perspective**1.2** : Front**1.3** : Back**1.4** : Left**1.5** : Right**1.6** : Top**1.7** : Bottom**1.8** : Perspective reference view**1.9** : Perspective reference view

Reproductions **1.8** and **1.9** are reference views showing the state of use. The broken lines in reproductions **1.8** and **1.9**, illustrating a hand and mobile phone, represent environmental structure that form no part of the claimed design. The broken lines shown in reproduction **1.7** represent portions of the holder for mobile phones that form no part of the claimed design.

1 Claim, 9 Drawing Sheets(56)
